UNITED STATES PATENT OFFICE.

JOHN OMWAKE, OF CINCINNATI, OHIO, ASSIGNOR TO THE UNITED STATES PRINTING COMPANY, OF SAME PLACE.

DESIGN FOR BACKS OF PLAYING-CARDS.

SPECIFICATION forming part of Design No. 23,238, dated May 1, 1894.

Application filed April 2, 1894. Serial No. 506,114. Term of patent 14 years.

To all whom it may concern:

Be it known that I, JOHN OMWAKE, a citizen of the United States, and a resident of Cincinnati, Hamilton county, State of Ohio, ⁵ have invented and produced a new and original Design for the Backs of Playing-Cards, of which the following is a full, clear, and exact description.

The drawing shows my design for the backs ¹⁰ of playing-cards.

The essential feature of my design consists in the representation of a cherub near each of the four corners of a card-back, the whole being surrounded by ornamental scroll-work.

In the drawing *a a* represent four conventional cherubim one near each corner of the card. Each cherub is surrounded by an ornamental scroll *bb*, and the space in the middle of the card-back is filled in by ornamental scrolls *cc*. ¹⁵ ²⁰

What I claim is—

The design for the backs of playing cards substantially as shown and described.

JOHN OMWAKE.
